UNITED STATES PATENT OFFICE.

WILLIAM M. SCOTT, OF PHILADELPHIA, PENNSYLVANIA.

COMBINED CONTROLLER AND CIRCUIT-BREAKER.

No. 872,154.

Specification of Letters Patent.

Patented Nov. 26, 1907.

Application filed April 9, 1907. Serial No. 367,249.

To all whom it may concern:

Be it known that I, WILLIAM M. SCOTT, a citizen of the United States, residing at Philadelphia, in the county of Philadelphia and 5 State of Pennsylvania, have invented a new and useful Combined Controller and Circuit-Breaker, of which the following is a specification.

My invention relates to automatic magnetic circuit breakers in combination with starting switches, controllers, and the like.

More particularly my invention relates to the combination of automatic magnetic circuit breakers with circuits or apparatus 15 in which the magnitude of current flow is greater at some periods than others. For example, in the starting of motors, and more especially when starting under load, the current flow during the starting period 20 is greater than the "running" current or the current flowing after the motor has attained desired speed. A circuit breaker included in circuit and adjusted to respond to current in excess of the running current would 25 respond to the excessive current during the starting period and so rupture the circuit.

It is the object of my invention, therefore, to provide a circuit breaker in combination with a starting switch, controller, or the 30 like, which shall respond during the starting period only to current which is excessive when considering starting currents, and which shall respond during running period to current which is excessive only as compared with running currents.

To this end I have the circuit breaker latch or trigger under the control of two tripping magnets, each adjusted to different loads or currents, and means provided in the 40 controller or starting switch, or any other switch, for including in circuit during the starting period the tripping magnet responsive to the greater current, and for cutting out that magnet and cutting in to circuit 45 during the running period the magnet adjusted to respond to lesser current.

My invention herein shown and described is a modification of the rheostat and circuit breaker of U. S. Patent No. 661,196 granted 50 me November 6, 1900.

My invention resides also in other features hereinafter described and pointed out in the claims.

For an illustration of one of the forms my

invention may take, reference is to be had 55 to the accompanying drawing, in which:

Figure 1 is a front elevational view of a three-pole circuit breaker, each of two of the poles having associated tripping magnets adjusted to respond to different currents. 160 Fig. 2 is a side elevation of the apparatus shown in Fig. 1. Fig. 3 is a plan view of the latch. Fig. 4 is a diagrammatic view showing a three-phase motor with starting switch or controller combined with an automatic 65 circuit breaker.

Referring to the drawings, B is a base of suitable insulating material such as slate, marble, or the like, upon which are secured three pairs of main terminal blocks 1 and 2 70 adapted to be bridged by the laminated movable contact member 3 supported by, but insulated from, the arm 4 pivoted to the bracket 5 at 6. Stationary and movable metallic shunt contacts 7 and 8 and the stationary and movable carbon shunt contacts 9 and 10 operate in a manner well understood in the art. Pivoted at 11, in the bracket 5, is an actuator lever 12 having the extension 13 pivoted at 14 to the link 15, 80 which, in turn, is pivoted at 16 to the arm 4. The three actuators are mechanically connected together by the connector or bar 17, and the operator's handle 18 is secured to the middle actuator 12, whereby all three movable contact members may be operated simultaneously by their respective toggles 13, 15. A single latch 19 pivoted to the bracket 5 of the middle switch engages the roller 20 pivoted at 21 in the middle actuator 12. 90 This latch 19 accordingly holds all three contact members in circuit closing position. The latch 19 has lateral extensions 22 and 23. The extension 23 is actuated by the two tripping magnets associated with the left 95 hand switch, while the extension 22 is actuated by the two tripping magnets associated with the right hand switch. A description of one pair of magnets will suffice for both, and for that purpose reference is to be had to 100 Fig. 2, where the latch extension 23 is shown to be in the path of travel of the member 24 forming an extension from the armature 25 of the magnet whose pole piece is 26, whose core is 27, and whose winding is 28. The 105 armature 25 is adjustable by screw to or away from the pole piece 26, so as to respond to different current strengths.

The second tripping magnet comprises the winding 29 surrounding the core 30 having the pole piece 31. The pivoted armature 32 is adjustable to and away from the pole piece 31 by the adjusting screw 33, so as to adjust the tripping magnet to respond to different current strengths. A link 34 is pivoted at its lower end to the armature 32 and at its upper end to the armature 25 of the first tripping magnet. In consequence, when either of the two tripping magnets is sufficiently energized the extension 23 of the latch will be struck or engaged, thus releasing the actuator 12 from the control of the latch 19, allowing the toggles to collapse and the laminated contact members to leave their stationary contact terminals, and later the separation of the metallic shunt contacts, and finally the separation of the carbon contacts 20 at which the final arcing occurs.

Referring to Fig. 4, 35, 36 and 37 constitute the conductors of a three-phase alternating current supply. The circuit breaker with its three movable contact members is shown diagrammatically upon the base B, and below the same upon the base C are supported the contacts of the starting switch or controller.

In the starting switch or controller is a handle 38 fastened upon the insulating bar 39 to which are secured the outer ends of five switch blades 40, 41, 42, 43 and 44, pivoted on the contacts 45, 46, 47, 48 and 49 respectively. The contacts 45, 47 and 49 constitute the terminals of the three conductors 50, 51 and 52, respectively leading to the three-phase alternating current motor M. A three-phase auto-converter or auto-transformer is shown at T, the three windings having a common connection at the center. The outer terminal of the winding 53 is connected by conductor 54 with the contact 48; similarly, the outer terminal of the winding 55 is connected by conductor 56 with the terminal 46, and the outer terminal of the winding 57 is connected by conductor 58 to one terminal of the tripping coil 29 of the right hand switch in the circuit breaker. A connection intermediate the terminals of the winding 53 is made by conductor 59 with the contact 60 on the starting switch or controller. Similarly, an intermediate tap is taken out of the winding 55 by conductor 61 connected to contact 62 on the starting switch; and similarly, a connection is made from an intermediate point in the winding 57 by conductor 63 with contact 64 on the starting switch. The tripping coil 29 of the left hand switch of the circuit breaker has one terminal connected to the main contact 2 and its other terminal by means of conductor 65 with the contact 66 on the starting switch. The contact 67 on the starting switch is in electrical communication with the middle contact 68 of the upper row of contacts on the starting switch,

the contact 69 connecting by conductor 70 with one terminal of the tripping coil 28; and the third contact 71 connects by conductor 72 with one terminal of the tripping coil 28 in the right hand switch of the circuit 70 breaker.

The operation is as follows: To start the motor M, the circuit breaker is closed by depressing the operator's handle 18 and latching the same in position shown in Fig. 2. 75 Then, the handle 38 of the controller or starting switch is thrown into the position shown in Fig. 4, so that the middle row of contacts are thrown into electrical communication with the lower row of contacts. Current 80 then flows from supply conductor 35 to terminal block 1 of the left hand switch of the circuit breaker, through the bridging contact member 3 to the main contact 2, then through the winding 29 of the tripping magnet, thence through conductor 65 to contact 66, to contact 46, to the outer terminal of converter winding 55, thence through conductor 61, contact 62, to contact 45, and through conductor 50 to the motor M. Similarly, current flows from supply conductor 37 through the right hand switch member of the circuit breaker, through the right hand tripping winding 29, conductor 58, to converter winding 57, through conductor 63 to contact 64, to contact 49, through conductor 52 to the motor M. And from the supply conductor 36, through the middle switch member of the circuit breaker, through conductor 73 to contact 68, to contact 67, to contact 48, through conductor 54, to converter winding 53, thence by conductor 59 to contact 60, to contact 47, thence by conductor 51 to the motor M. With the parts in this position, the motor is subjected to electric 105 pressure less than line pressure and starts without taking too great a current from the line. With the parts remaining in the position shown, the motor accelerates and the current flowing through it becomes reduced 110 in magnitude. The current flow during this starting period, however, is in excess of the current flowing through the motor when it has attained full speed conditions. If, during this starting period, the current should 115 rise to an abnormal value, as compared with usual starting currents, which are in themselves greater than running currents, the winding 29, of the left hand pair of tripping coils, for example, when the unusual loading 120 happens to be on that branch, will sufficiently energize its core 30 to attract its armature 32 to actuate the latch 19 to trip the circuit breaker and open all three poles. Because the starting currents are larger than the running currents, the tripping magnet whose winding is 29 is so adjusted that it will respond only to currents in excess of the allowable starting currents. The same, of course, is true of the other tripping magnet whose 125 130

winding is 29 associated with the bridging member of the right hand switch member. And obviously, if the overloading should occur in the branch including the right hand 5 switch member, its magnet 29 would respond to trip the circuit breaker. If neither of the tripping magnets 29 are energized sufficiently during the starting period to trip the circuit breaker, the motor comes up to considerable 10 speed, whereupon the operator quickly throws the handle 38 of the controller upwardly and closes the switch in upward position, in which case the contact 45 is put into communication with contact 69; contact 47 15 with contact 68; and contact 49 with contact 71, contacts 46 and 48 remaining dead. With the parts in such position, the tripping magnets 29, responsive to current in excess of starting currents, have been cut out of circuit and the tripping magnets 28, responsive 20 to currents in excess of running currents only, have been cut in to circuit. The path of current is then simply from conductor 35, through the left hand switch, its tripping 25 coil 28, conductor 70, contact 69, contact 45, and thence by conductor 50 to the motor M; and from conductor 36 through the middle switch member, through conductor 73 to contact 68, to contact 47, and thence by conductor 51 to the motor; and from supply conductor 37 through the right hand switch member, through its tripping coil 28, conductor 72, to contact 71, to contact 49, and thence by conductor 52 to the motor, which 35 is then subjected to full line pressure and then runs at full speed. If for any reason, the motor should be overloaded or a current in excess of the running current should obtain, either one or the other, or both of the 40 tripping coils 28 will energize its core 27 and attract its armature 25 to actuate the latch, whereupon the circuit breaker will open at all three poles.

From the foregoing description, it is apparent 45 that by means of the control switch and the additional tripping magnet, as 29, the system is afforded with circuit breaker protection through the starting period, the adjustment of the tripping magnet being such 50 that the circuit breaker will open at an ampere point in excess of the ampere point at which it will open during running period. And during running period the tripping magnet responsive to less current is in circuit.

55 While I have here shown a starting switch or controller associated with an auto-converter, it is to be understood also that the same may be associated with an ordinary starting device, such as a rheostat or adjustable resistance. Furthermore, while I have here shown an alternating current system, my invention is applicable equally well to a direct current system. And though I have here shown a circuit breaker with three 60 poles, it is to be understood that my invention

is applicable to a circuit breaker with any number of poles, and, in fact, with a single pole as may be well imagined when considering the right or left hand switch only of the circuit breaker as herein shown. 70

What I claim is:

1. In combination with a controlling switch, an automatic magnetic circuit breaker, and means controlled by said controlling switch for changing the ampere-point of operation of said circuit breaker, said means comprising independent electro-magnetic tripping devices, and means associated with said controlling switch for including said electro-magnetic tripping devices in circuit alternately. 75

2. The combination with a controller, of a circuit breaker, a plurality of independent electro-magnetic tripping devices each adapted to trip said circuit breaker and each 85 adapted to be adjusted to respond to different current strengths, and contacts in said controller for including said electro-magnetic tripping devices in circuit at different times.

3. The combination with a controller, of a circuit breaker, a plurality of independent electro-magnetic tripping devices, and a contact in said controller for including in circuit during starting period a tripping device responsive to greater current strength, and 95 another contact in said controller for including in circuit after starting period a tripping device responsive to less current. 90

4. The combination with a supply circuit, of a motor, a starting switch and circuit breaker associated with said motor, an electro-magnetic tripping device responsive to greater current and included in circuit during the period of starting said motor, and another electro-responsive device responsive to less current included in circuit after 105 starting.

5. The combination with a supply circuit, of a motor, a starting switch and circuit breaker associated therewith, means in said 110 starting switch for including in circuit during starting period an electro-magnetic tripping device responsive to greater current, and means in said starting switch for cutting out said electro-magnetic tripping device after 115 said motor is started and including in circuit another electro-magnetic tripping device responsive to less current.

6. The combination with a polyphase supply circuit, of a polyphase motor, a circuit breaker and a starting switch associated therewith, means in said starting switch for including in one branch of said circuit during starting period an electro-magnetic tripping device responsive to greater current, and 120 means in said starting switch for cutting out said electro-magnetic tripping device and including in the same branch after the motor is started an electro-magnetic tripping device responsive to less current. 125

7. The combination with a polyphase supply circuit, of a polyphase motor, a starting switch, a circuit breaker having a contact member in each branch of said circuit, a plurality of electro-magnetic tripping devices associated with each of a plurality of said contact members, one of the electro-magnetic tripping devices associated with a given contact member being responsive to greater current than another associated with the same contact member, and means in said starting switch for including said differently responsive tripping devices in circuit at different times.
8. In combination, a circuit breaker having a plurality of independent tripping devices responsive to different circuit conditions, and a switch for including in circuit any one of said tripping devices.
9. In combination, a circuit breaker comprising a movable contact member, means for restraining said contact member in normal position, a plurality of independent tripping devices responsive to different loads, and a switch for including in circuit during desired periods any one of said tripping devices.
10. In combination, a circuit breaker hav-

ing a plurality of independent tripping devices, each adjustable to respond to a predetermined electrical condition, and a switch for including said tripping devices in circuit alternately.

11. In combination, a circuit breaker having a plurality of independent tripping devices, each adjustable independently of the other or others to respond to any desired electrical condition in the circuit, and a switch for including said tripping devices in circuit alternately.

12. In combination, a multi-pole circuit breaker, independent tripping devices associated with each of two or more poles of said breaker, each tripping device being adjustable independently of the others to respond to any desired electrical condition, and a switch for including said tripping devices in circuit alternately.

In testimony whereof I have hereunto affixed my signature in the presence of the two subscribing witnesses.

WILLIAM M. SCOTT.
